Application January 3, 1942, Serial No. 425,568

33 Claims. (Cl. 62—121)

This invention relates to a new method of discharging carbon dioxide for extinguishing fires, more particularly outdoor fires, by direct application of the extinguishing medium, and apparatus for carrying out said method.

In patent numbered 2,143,311, issued to Eric Geertz, there is disclosed and claimed a method of extinguishing fires which involves the use of liquid carbon dioxide at a constant, subatmospheric temperature and its corresponding vapor pressure, as the extinguishing medium. One of the outstanding novel features of this patented method, when compared with prior methods employing carbon dioxide at atmospheric temperature, is the improvement in the effectiveness and range of application that results from the high percentage of snow yield obtained when the low temperature liquid carbon dioxide is permitted to suddenly expand. Of course, the lower the temperature at which the liquid carbon dioxide is discharged, the greater the percentage of yield of snow.

The energy possessed by a discharged stream of fire extinguishing medium is, of course, the factor which determines the ability of the stream to penetrate strong air currents rising above and around a fire zone and to counteract or overcome high velocity natural winds. The energy of any moving body is equal to one-half of the product of the mass of the body times the square of its velocity. Therefore, when it is considered that a discharged stream of carbon dioxide is made up of a mixture of snow particles and vapors and the snow is many times more dense, or possesses much greater mass per unit of volume, than the vapors, it will be appreciated that the percentage of snow possessed by a stream of this extinguishing medium has a very direct bearing on its energy. As a discharged stream of carbon dioxide made up, for example, of forty-five percent snow, the yield provided when liquid carbon dioxide at a temperature of 0° F. is suddenly released, is more dense; i. e., possesses more mass per unit of volume, than a stream made up of twenty percent snow, the yield provided when liquid carbon dioxide at a temperature of 86° F. is suddenly released, the first mentioned stream must necessarily possess more energy. For a given velocity and amount of air resistance, therefore, the forty-five percent snow stream is capable of being projected to and providing an extinguishing concentration at a greater distance than the twenty percent snow stream.

With the above facts in mind, experiments were carried on for the purpose of developing a way of

increasing the extinguishing range of a discharge of carbon dioxide, obtained from any given temperature liquid. As any improvement in energy obtained as a result of increasing the velocity of discharge would impose a penalty in the form of greater air entrainment by the discharged medium, and as any reasonable increase in velocity that might be desired to effect an increase in energy could be obtained by merely reducing the diameter of the discharge opening for the carbon dioxide, the experiments were limited to attempts to increase the mass per unit of volume of the discharge and reduce the effect of air resistance.

As a result of these experiments, it was finally determined that by separating all or substantially all of the snow from a substantial portion of or all of the vapors and collecting and concentrating the thus separated snow into one portion of the cross sectional area of the discharged stream, the density of this stream, or the compact arrangement of the snow particles, was such that less surface was directly exposed to the resistance offered by the air. The ratio of air resistance to mass per unit of volume of this stream portion, therefore, was very much more favorable than that of any corresponding unit of volume of a stream which was formed by discharging the same amount of carbon dioxide at the same rate but with the snow distributed in a normal or natural manner throughout the entire cross sectional area of the stream. Due to the unusually high mass to air resistance ratio possessed by this concentrated stream portion, its effective range and penetrating characteristics were found to be easily twice those of a stream of equal volume which had its snow distributed in a normal manner.

It was further determined that if the separated snow was discharged in such a manner as to form the core of the complete, composite discharge or stream and the separated vapors were arranged to enclose or surround the snow core, the vapors not only shielded the snow from the resistance offered by the air but they provided the further advantage of retarding sublimation of the snow with the result that the snow core retained its density and compact arrangement for a greater length of time and, therefore, did not lose its energy as readily as would be the case if the snow particles started to move laterally and to sublime at a rapid rate as soon as they were discharged into the atmosphere. By condensing the snow core into a stream portion of comparatively small diameter, it was possible to project the same a long distance from the discharge device, or noz-

zle, and yet maintain a fire extinguishing concentration of carbon dioxide even when the discharge was called upon to buck or oppose high velocity natural winds.

It will be appreciated that the above noted improvements were effected independently of any regard for the temperature of the liquid carbon dioxide employed as a source of supply and the percentage of snow yield. Of course, the effectiveness of this novel form of discharge is increased in direct proportion to any increase in the percentage of snow possessed by the discharge. Therefore, the use of this carbon dioxide discharge method and apparatus in connection with the low temperature carbon dioxide covered by the aforementioned patent to Eric Geertz provides the most satisfactory results.

It is the primary object of this invention to provide an improved method of discharging carbon dioxide for extinguishing fires.

A further important object of the invention is to provide apparatus for discharging carbon dioxide for the extinguishment of outdoor fires by direct application of the extinguishing medium.

Another object of the invention is the provision of a method of increasing the effective range and penetrating characteristics of a discharge of carbon dioxide so that it may be successfully employed for combatting fires which involve relatively large areas, such as the surface of a sizable body of inflammable liquids, or which is burning at a location that cannot be closely approached by persons directing the discharge, either because of the inaccessibility of the location of the fire or the intensity of the heat developed by the same, and for fighting outdoor fires where high velocity natural winds frequently offer considerable opposition to the proper application of this type of extinguishing medium.

Other objects and advantages of the invention will be apparent during the course of the following description.

In the accompanying drawings forming a part of this specification and in which like numerals are employed to designate like parts throughout the same,

Figure 1 is a front elevational view of the preferred form of carbon dioxide discharge apparatus embodying this invention.

Figure 2 is a transverse sectional view taken on line 2—2 of Fig. 1.

Figure 3 is a detail, front elevational view of a shank or stem element which forms a part of the discharge apparatus of Figs. 1 and 2.

Figure 4 is a detail, inner or rear elevational view of a deflector member that is mounted on and directly cooperates with the stem or shank member of Fig. 3.

Figure 5 is a detail perspective view of one of a circular series of flow controlling or directing units which is incorporated in the nozzle of Figs. 1 and 2.

Figures 6 to 8 inclusive are projection views of a deflecting and separating element which forms a part of each one of the units illustrated in Fig. 5.

Figure 9 is a front elevational view, partly broken away, of one of the earliest forms of discharge apparatus which was developed to carry out the novel method of this invention, and

Figure 10 is a transverse sectional view taken on lines 10—10 of Fig. 9.

In the drawings, wherein for the purpose of illustration are shown certain embodiments of this invention, and first particularly referring

to Figs. 1 to 8 inclusive, the reference character 11, in Fig. 2, designates a pipe which is employed for supplying the liquid carbon dioxide to the discharge apparatus. This pipe may be considered as representative of either a "playpipe" which is attached to the outer end of a fire hose and used in handling the discharge apparatus or a pipe which forms a part of a "fixed" system. To the threaded end 12 of this pipe there is connected one end of the stem or shank 13. This stem or shank is provided with a bore 14, see Figs. 2 and 3, for delivering the liquid CO₂ from the pipe 11 to the interior of the body of the discharge apparatus. The outer end 15 of this bore communicates with the interior of a deflector element, which will be described in detail at a later point, and cooperates with this element to form a flow path for the liquid carbon dioxide. This outer end of the stem or shank body has formed thereon a radially extending flange 16 which is formed with a circular series of orifices 17 through which the liquid carbon dioxide is released to permit sudden expansion so that its pressure will drop below 75 pounds per square inch, absolute, which will cause a certain percentage of the liquid to flash to snow and the remainder to vaporize. This flange, additionally, is provided with a circular series of internally threaded openings 18, for a purpose to be explained at a later point. Externally, the stem or shank is shaped to provide the rearwardly curved or flared surface 19 that terminates in a shoulder 20.

Figs. 1, 2 and 4 disclose the deflector element 21 which is secured to the flange 16 of the stem or shank 13 by means of the series of screws 22 that are threaded into the holes 18 formed in said flange. This deflector is partially hollowed out so as to control the direction of flow 40 of the liquid carbon dioxide to the discharge orifices 17. For this purpose, the interior of the deflector is provided with a conically shaped projection 23 that is axially aligned with the bore 14 of the shank or stem. Outwardly of this 45 spreading projection 23, the interior of the deflector is provided with the curved surfaces 24 that function to change the direction of flow of the liquid carbon dioxide so that it will be directed rearwardly to the discharge orifices. The inner 50 or rear portion of the deflector 21 is belled or curved outwardly at 25 to form an internal curved surface 26 that directly opposes and cooperates with the curved exterior surface 19 of the stem or shank 13. It will be seen, by inspecting Fig. 2, that these cooperating surfaces 19 and 26 diverge with respect to each other, when considered in any radial section, to form an annular passageway that gradually increases in depth. This increase in the passageway permits further 55 expansion of the released medium so that the pressure of the same will drop still further and provide for further flashing of whatever liquid may happen to remain as a part of the mixture.

The outer end portion or front of the deflector is illustrated in Figs. 1 and 2 as being of ribbed formation. These ribs 27 radiate from the center or axis of the deflector to form valleys 28. Fig. 2 shows these valleys as having curved surfaces 29 which will deflect forwardly any of the discharge medium which comes in contact with the same.

A chambered body or casing is provided for enclosing the deflector 21 and the cooperating portion of the stem or shank 13, as well as other structural elements which will be described at

a later point. This chambered body or casing is formed by the inner and outer portions 30 and 31 respectively. The inner portion 30 is dished and is centrally cut away at 32 to allow the stem or shank 13 to pass therethrough. The shoulder 28 forming the flared portion of the stem or shank acts as a seat or an abutment for the portion of the body part 30, which surrounds the opening 32, to bear against. The body or casing part 30 may be secured to this shoulder portion 28 of the stem or shank 13 by any suitable means, such as by welding or the use of suitable screws. The outer part 31 of the body or casing is illustrated as being of cylindrical shape. The inner edge portion of the same overlaps or is telescoped with respect to the outer marginal portion of the inner part 30 to provide a lapped joint 33. This joint may be rendered permanent by welding or by any other suitable means. It will be seen by inspecting Figs. 1 and 2 that the body or casing of the discharge apparatus cooperates with the stem or shank 13 to provide a closed rear wall while leaving the front entirely open. The body or casing additionally cooperates with the stem or shank 13 and the deflector 21 to form an annular chamber for receiving the circular series of flow controlling and directing units 34, one of which is illustrated in detail in Fig. 5.

These units 34 are equally spaced around and extend radially of the stem or shank 13 and the deflector 21. Each one of the units includes a semi-circular or semi-cylindrical band 35 which is flanged at 36, or at both of its longitudinal edges. The inner transverse edge 37 of each one of these bands is suitably anchored either in close proximity to or in contact with the periphery of the flared portion or surface 19 of the stem or shank 13. The outer edge 38 of each one of these bands 35 terminates in the plane of the outer face or side of the mechanism; i. e., in the plane of the outer edge of the body or casing part 31 and the outer edges of the ribs 27 formed on the deflector 21.

The opposite sides of each one of these units 34 are formed by wall members 39 which lie inside of the edge flanges 36 and are suitably secured thereto. By inspecting Figs. 1 and 5, it will be seen that the opposed side walls of each adjacent pair of units 34 are formed by a single piece of sheet material. The center or intermediate portion of each one of these side wall forming pieces is designated in these two figures by the reference character 40. These portions 40 function to bridge the gap or space between the inner edges or sides of adjacent units 34. They bear against the peripheral edge of the flared inner portion 25 of the deflector 21. These side wall forming pieces 39-40, therefore, interconnect adjacent units 34 and thereby act as spacers and bracing means for the same. The bands 35 of the unit may be suitably connected or attached to the inner body or casing part 30 to provide additional rigidity for the units and, in addition, to cause the units to brace and reinforce the body or casing part 30.

Figs. 1, 2 and 5 disclose apertures 41 formed in the side walls 39 of the several units. These apertures, or openings, are arranged in the outer or front halves of the side walls 39; i. e., relatively close to the outer edges 38 of the bands 35. Each flow controlling and directing unit 34 has mounted within the same a plow-shaped deflecting and separating element 42. These elements

are of V or wedge shape in section with securing flanges 43 formed at the sides thereof. These mounting flanges are employed for securing, such as by welding, the element in its proper place within a unit 34. Figs. 2 and 5 disclose these deflecting and separating elements as being arranged with respect to the side wall openings 41 so that the laterally sloping surfaces 44 of each element will split or spread any material flowing through the interior of a unit 34 and engaging the same so that this material will be deflected through the cooperating side wall openings 41. Figs. 2 and 5 disclose these deflecting and separating elements as being arranged so that their outer transverse edges 45 are spaced from the inner surfaces of the outer end portions of their associated bands 35. In other words, a space or gap is left between the inner surface of the band 35 of each unit 34 and the outer edge 45 of its associated deflecting and separating element 42 through which material may flow to the outer edge 38 of the band 35.

The mode of operation of this discharge apparatus or nozzle now will be described. Liquid carbon dioxide of any desired temperature will be delivered to the bore of the shank or stem 13 by the supply pipe 11. This liquid carbon dioxide flows through the open end 15 and into the interior of the deflector 21. The conical point 23 formed on the inside of this deflector splits the liquid carbon dioxide as it leaves the open end 15 and directs the flowing medium radially outwardly in all directions. The curved surface 24 that surrounds the conical projection 23 causes the outwardly deflected liquid to smoothly reverse its direction of flow so that it will be delivered to the discharge orifices 17.

The sudden expansion of the liquid carbon dioxide as it leaves the orifices 17 causes the liquid to flash and vaporize. The carbon dioxide that enters the space formed between outwardly flared surfaces 19 and 26, therefore, takes the form of a mixture of snow and vapors. Depending upon the temperature of the liquid carbon dioxide flowing through the stem or shank 13, a certain percentage of the same will flash into snow. The remainder of the liquid will be vaporized. The expansion and pressure drop that occurs while the medium is flowing between the outwardly flaring surfaces 19 and 26 will be sufficient to cause any liquid which may remain in the mixture to be converted. The entire discharge from the peripheral mouth, formed by the peripheral edges of the surfaces 19 and 26, will consist of a mixture of snow and vapors.

The snow and vapor mixture, as it leaves the peripheral mouth formed by the stem or shank 13 and the deflector 21 will be flowing in a radial direction. Some portions of the mixture will pass directly into the various flow controlling and directing units 34. The remainder of the mixture will be split and deflected laterally in opposite directions by the axially extending portions 40 of the side wall forming pieces 39. These portions of the mixture, therefore, will be directed into the several units 34.

All of the snow and vapor mixture discharged from the aforesaid peripheral mouth would flow in a truly radial direction, or in a straight line, if it were left alone or unobstructed. The flow controlling and directing units 34, however, deflect this truly radial or straight line flow and convert it into a curvilinear flow or motion. The inner surfaces of the bands 35 of the units are

responsible for this change in direction of motion.

It is a well recognized law or principle of physics that any object or material which is set in motion will travel in a straight line unless some force is applied which will deflect it from said straight line. Additionally, the force required to deflect the object or material from its straight line motion depends on the velocity and the mass or density of the object or material being deflected.

The band portions 35 of the flow controlling and directing units 34 are called upon to convert the intended straight line motion of the snow and vapor mixture into a curvilinear motion. These bands, therefore, provide the force referred to in the above set forth principle of physics. As the carbon dioxide snow of the mixture is many times more dense than the carbon dioxide vapors, and as the velocity of both of these components is the same, the snow offers more resistance to the deflecting force. The snow, therefore, will move to the outer side of the curvilinear path of flow the material is compelled to assume by the curved band 35 of each unit. The snow, in seeking this outer portion of the path, will crowd or force the vapors inwardly away from the inner surface of the respective bands 35. The difference in density of the snow as compared to the vapors, therefore, effects a segregation of these two components. The snow is segregated at and close to the outer side of the curvilinear path and the vapors are segregated on the inner side of the path.

As the segregated snow and vapors reach the outer side of each one of the flow controlling and directing units 34, the snow passes through the gap or space left between the inner surface of its band 35 and the outer edge of its flow splitting and separating element 42. The inwardly positioned, segregated vapors, however, strike the sloping surfaces 44 of an element 42 and are directed laterally through the side wall openings 41 into the portions of the body or casing which lie between adjacent units 34. The thus separated snow passes radially inwardly beyond the edge 38 of each band 35 and is directed into one of the valleys 28 of the deflector 21. The curved inner surface 29 of each valley 28 deflects the snow so that it will flow or will be discharged to the atmosphere in an axial direction with respect to the entire apparatus. This discharge of all of the separated snow from all of the units 34 causes the same to be assembled into a compact, dense stream.

The separated vapors will leave the spaces between the adjacent units 34 and will flow in an axial direction relative to the discharge apparatus. The vapors, however, are discharged outwardly of the snow stream so that the resultant composite discharge will be made up of a dense snow core surrounded by or enclosed in a vapor tube or envelope.

From this description of the mode of operation of the discharge apparatus disclosed in Figs. 1 to 8 inclusive, it will be appreciated that the apparatus fully carries out the principles developed as a result of the research experiments referred to in the introductory portion of this description of the invention. The carbon dioxide discharge obtained by means of this apparatus has been found to be extremely effective in combating outdoor fires that are burning in the presence of high velocity natural winds. For example, an entirely satisfactory fire extinguish-

ing concentration of carbon dioxide is provided up to a distance of approximately twenty-five feet when wind velocities of from forty-five to fifty miles an hour are encountered. In the presence of normal winds of approximately fifteen miles an hour velocity, an entirely satisfactory fire extinguishing concentration exists up to approximately thirty-five feet from the discharge apparatus.

10 The extinguishing concentrations just referred to are, for example, suitable for and completely effective in extinguishing gasoline fires when the discharge apparatus is supplied with liquid carbon dioxide through hose or pipe lines of one and a half inch diameters. 15 Coming now to the disclosure of Figs. 9 and 10, the reference character 46 designates the stem or shank of this modified form of carbon dioxide discharge apparatus. This stem or shank is adapted to be connected to any suitable supply 20 pipe which in turn is connected to a source of supply of liquid carbon dioxide at any desired temperature. The bore 47 of this stem or shank 46 is provided with a discharge or release orifice 48 at its outer end and through which liquid 25 carbon dioxide is permitted to suddenly expand into the inner part 49 of the discharge apparatus body or casing. This sudden release of the liquid carbon dioxide permits the same to expand for conversion into a mixture of carbon dioxide snow 30 and vapors.

A deflector 50 is attached to the rear wall 51 of the body or casing part 49 by means of the screws 52. Spacers 53 are provided between the deflector 50 and the body or casing wall 51 to 35 provide an expansion chamber for the carbon dioxide mixture. At the periphery of the rear portion of the deflector 50 an annular mouth 55 is formed through which the carbon dioxide mixture is released into the interior of the body or 40 casing of the discharge apparatus. The carbon dioxide snow and vapor mixture released or discharged from this mouth 55 would normally travel in a truly radial direction or in straight lines extending radially of the axis of 45 the apparatus.

The inner surface 56 of the inner or rear body or casing part 49 is dish-shaped to provide a curved peripheral portion. This curved portion cooperates with a correspondingly curved surface portion 57 formed on the interior of the outer body or casing portion 58. These two curved surface portions function to convert the straight line motion of the carbon dioxide mixture into a curvilinear motion which, as has been 55 explained above, will bring about a segregation of the snow and the vapors with the snow seeking the outer portion of the path as a result of its greater density.

The outer body or casing part 58 is detachably 60 secured to the inner body or casing part 49 by means of a suitable number of screws 59. These screws 59 are received in holes formed in ribs or projections 60 and 61 which are arranged at uniformly spaced intervals on the curved surface portions 56 and 57 above referred to. Fig. 9 clearly discloses these ribs or projections as being of wedge shape with their edges 62 presented to the flow of carbon dioxide mixture from the aforementioned chamber mouth 55. 65 These wedge shaped projections, therefore, will split the flow laterally in opposite directions.

The outer body or casing part 58 is constructed to provide an internal frusto-conical wall portion 63 that is formed with a discharge opening 64 at its apex or outer edge. Radially arranged 70

75

slots or openings 65 are formed in this wall 63. Deflecting and separating elements or barriers 66 are formed around the inner margins of the slots or openings 65. These elements or barriers project inwardly of the frusto-conical wall 63 and terminate at their inner edges in parallelism with the conical surface 50a of the deflector 50. In the spaces between adjacent deflecting and separating elements or barriers 66, the inner surface of the frusto-conical wall 63 acts to control the direction of flow of the carbon dioxide mixture which is delivered into the space between this wall 63 and the conical surface 50a of the deflector 50. These surface portions of the wall 63, therefore, cooperate with the curved inner surface portions 56 and 57 in effecting segregation of the snow and the vapors. The segregated snow, which has sought the outer side of the curvilinear path formed by the surfaces 56 and 57, will hug the inner exposed surface portions of the frusto-conical wall 63 and will crowd the segregated vapors toward the conical front surface 50a of the deflector 50. The thus segregated vapors will escape through the bores of the deflecting and separating elements or barriers 66 to be released through their associated slots or openings 65 into the space 67 which is formed by the cylindrical wall 68 of the outer body or casing part 58. This separated vapor component of the carbon dioxide mixture will be discharged from the space 67 into the atmosphere in the form of a tubular stream or envelope.

The separated snow will pass along the exposed inner surface portions of the frusto-conical wall 63 until it reaches the discharge opening 64 when it will be released to the atmosphere. The discharged, separated snow, therefore, will form a condensed core for the composite discharge. That is to say, the dense snow discharge will form a core stream that is enclosed within the tubular vapor stream discharged from the space 67.

From the above description, it will be seen that this discharge apparatus of Figs. 9 and 10 operates in the same general manner as the discharge apparatus of Figs. 1 to 8 inclusive. In both structures, liquid carbon dioxide is discharged or released in a manner to permit sudden expansion of the same and to cause it to be converted into a mixture of snow and vapors. The mixture is then caused to flow truly radially or to at least start to partake of straight line motion.

Both structures then provide means for converting the straight line motion of the mixture to a curvilinear motion which will effect segregation of the snow and the vapors. Deflecting and separating elements function to part or divide the segregated snow from the segregated vapors and to cause the vapors to escape through suitable openings into a discharge zone or chamber which is formed by a peripheral wall part of the outer body or casing portion. The separated snow is brought together and discharged as the core of the final composite stream.

The apparatus of Figs. 1 to 8 inclusive is the preferred embodiment of the invention because it effects more complete separation of the snow from the vapors and, for that reason, is capable of handling to a better advantage the higher percentage of snow yield which is obtained from the lower temperatured liquid.

It is to be understood that the forms of this invention herewith shown and described are to be

taken as examples of the same, and that various changes in the shape, size, and arrangement of parts may be resorted to without departing from the spirit of the invention or the scope of the subjoined claims.

Having thus described the invention, I claim:

1. A method of discharging liquid carbon dioxide for fire extinguishing purposes, comprising conducting the liquid through a path of confinement to a region of release, releasing the liquid from said path to permit sudden expansion of the same to effect its conversion into a mixture of carbon dioxide snow and vapors, deflecting the flowing mixture to effect a departure from its normal straight line path of movement, continuing the deflection of the moving mixture until the difference in density of the snow and the vapors effects a substantial segregation of these components into different portions of the flow, and finally discharging the carbon dioxide to the atmosphere in its thus segregated condition.

2. A method of discharging liquid carbon dioxide for fire extinguishing purposes, comprising conducting the liquid through a path of confinement to a region of release, releasing the liquid from said path to permit sudden expansion of the same to effect its conversion into a mixture of carbon dioxide snow and vapors, deflecting the flowing mixture to effect a departure from its normal straight line path of movement, continuing the deflection of the moving mixture until the difference in density of the snow and the vapors effects a substantial segregation of these components into different portions of the flow, and finally discharging the carbon dioxide to the atmosphere with the segregated snow forming the core of the stream.

3. A method of discharging liquid carbon dioxide for fire extinguishing purposes, comprising conducting the liquid through a path of confinement to a region of release, releasing the liquid from said path to permit sudden expansion of the same to effect its conversion into a mixture of carbon dioxide snow and vapors, deflecting the flowing mixture to effect a departure from its normal straight line path of movement, continuing the deflection of the moving mixture until the difference in density of the snow and the vapors effects a substantial segregation of these components into different portions of the flow, and finally discharging the carbon dioxide to the atmosphere with the segregated snow and vapors emerging from separate openings.

4. A method of discharging liquid carbon dioxide for fire extinguishing purposes, comprising conducting the liquid through a path of confinement to a region of release, releasing the liquid from said path to permit sudden expansion of the same to effect its conversion into a mixture of carbon dioxide snow and vapors, deflecting the flowing mixture to effect a departure from its normal straight line path of movement, continuing the deflection of the moving mixture until the difference in density of the snow and the vapors effects a substantial segregation of these components into different portions of the flow, and finally discharging the carbon dioxide to the atmosphere with the segregated snow emerging in a single condensed stream and with the segregated vapors emerging as several streams arranged to merge and encircle or surround said snow stream.

5. A method of discharging liquid carbon dioxide for fire extinguishing purposes, comprising

conducting the liquid through a path of confinement to a region of release, releasing the liquid from said path to permit sudden expansion of the same to effect its conversion into a mixture of carbon dioxide snow and vapors, deflecting the flowing mixture to effect a departure from its normal straight line path of movement, continuing the deflection of the moving mixture until the difference in density of the snow and the vapors effects a substantial segregation of these components into different portions of the flow, and finally discharging the carbon dioxide to the atmosphere in the form of a composite stream with the segregated snow forming a dense core for the stream and with the segregated vapors forming an enclosing envelope.

6. A method of discharging liquid carbon dioxide for fire extinguishing purposes, comprising conducting the liquid through a path of confinement to a region of release, releasing the liquid from said path to permit sudden expansion of the same to effect its conversion into a mixture of carbon dioxide snow and vapors, deflecting the flowing mixture to effect a departure from its normal straight line path of movement, continuing the deflection of the moving mixture until the difference in density of the snow and the vapors effects a substantial segregation of these components into different portions of the flow, effecting separation of the segregated snow and vapors, and finally discharging the separated snow and vapors through different openings to the atmosphere.

7. A method of discharging liquid carbon dioxide for fire extinguishing purposes, comprising conducting the liquid through a path of confinement to a region of release, releasing the liquid from said path through an orifice to permit sudden expansion of the same to effect its conversion into a mixture of carbon dioxide snow and vapors, deflecting the flowing mixture radially outwardly and then inwardly with respect to the orifice through a curvilinear path of sufficient length to cause the difference in density of the snow and the vapors to effect a substantial segregation of these components with the snow seeking the outer side of the curve, and finally discharging the carbon dioxide to the atmosphere in its segregated condition.

8. A method of discharging liquid carbon dioxide for fire extinguishing purposes, comprising conducting the liquid through a path of confinement to a region of release, releasing the liquid from said path through an orifice to permit sudden expansion of the same to effect its conversion into a mixture of carbon dioxide snow and vapors, deflecting the flowing mixture radially outwardly and then inwardly through a curvilinear path of sufficient length to cause the difference in density of the snow and the vapors to effect a substantial segregation of these components with the snow seeking the outer side of the curve, continuing the deflection of the segregated snow until it can be discharged to the atmosphere in the form of a single dense stream, and releasing the segregated vapors so that they will form an enclosing envelope for the snow stream.

9. A method of discharging liquid carbon dioxide for fire extinguishing purposes, comprising conducting the liquid through a path of confinement to a region of release, releasing the liquid from said path through an orifice to permit sudden expansion of the same to effect its con-

version into a mixture of carbon dioxide snow and vapors, deflecting the flowing mixture radially outwardly and then inwardly through a curvilinear path of sufficient length to cause the difference in density of the snow and the vapors to effect a substantial segregation of these components with the snow seeking the outer side of the curve, effecting separation of the segregated snow and vapors, and finally discharging the separated snow and vapors through different openings to the atmosphere.

10. A method of discharging liquid carbon dioxide for fire extinguishing purposes, comprising conducting the liquid through a path of confinement to a region of release, releasing the liquid from said path through an orifice to permit sudden expansion of the same to effect its conversion into a mixture of carbon dioxide snow and vapors, deflecting the flowing mixture radially outwardly and then inwardly through a curvilinear path of sufficient length to cause the difference in density of the snow and the vapors to effect a substantial segregation of these components with the snow seeking the outer side of the curve, effecting separation of the segregated snow and vapors, and finally discharging the separated snow and vapors to the atmosphere in the form of a composite stream with the separated snow forming a dense core for the stream and with the separated vapors forming an enclosing envelope.

11. Fire extinguishing apparatus for discharging liquid carbon dioxide, comprising a chambered body, a tubular stem carried by the body and having an orifice through which carbon dioxide may be released into the interior of the body to form a mixture of snow and vapors therein, means within the body for causing the snow and the vapors of the mixture to become segregated while flowing therethrough, and means for effecting discharge of the segregated snow and vapors to the atmosphere.

12. Fire extinguishing apparatus for discharging liquid carbon dioxide, comprising a chambered body, a tubular stem carried by the body and having an orifice through which carbon dioxide may be released into the interior of the body to form a mixture of snow and vapors therein, means within the body for causing the mixture to travel a substantially curvilinear path of sufficient length to cause the difference in density of the snow and the vapors to effect a substantial segregation of these components, and means for effecting discharge of the segregated snow and vapors to the atmosphere.

13. Fire extinguishing apparatus for discharging liquid carbon dioxide, comprising a chambered body, a tubular stem carried by the body and having an orifice through which liquid carbon dioxide may be released into the interior of the body to form a mixture of snow and vapors therein, means within the body for causing the snow and the vapors of the mixture to become segregated while flowing therethrough, and means for effecting discharge of the segregated snow and vapors to the atmosphere in a composite stream with the snow forming the core thereof.

14. Fire extinguishing apparatus for discharging liquid carbon dioxide, comprising a chambered body, a tubular stem carried by the body and having an orifice through which liquid carbon dioxide may be released into the interior of the body to form a mixture of snow and vapors therein, means within the body for causing the mixture to travel a substantially curvilinear path of

sufficient length to cause the difference in density of the snow and the vapors to effect a substantial segregation of these components, and means for effecting discharge of the segregated snow and vapors to the atmosphere in a composite stream with the snow forming the core thereof.

15. Fire extinguishing apparatus for discharging liquid carbon dioxide, comprising a chambered body, a tubular stem carried by the body and providing an inlet orifice through which liquid carbon dioxide may be released into the interior of the body to form a mixture of snow and vapors therein, means within the body for causing the snow and the vapors of the mixture to become segregated while flowing therethrough, means for effecting discharge of the segregated snow to the atmosphere in a single dense stream, and means for effecting discharge of the segregated vapors to the atmosphere as several streams arranged to merge and encircle or surround such snow stream.

16. Fire extinguishing apparatus for discharging liquid carbon dioxide, comprising a chambered body, a tubular stem carried by the body and providing an inlet orifice through which liquid carbon dioxide may be released into the interior of the body to form a mixture of snow and vapors therein, means within the body for causing the mixture to travel a substantially curvilinear path of sufficient length to cause the difference in density of the snow and the vapors to effect a substantial segregation of these components, means for effecting discharge of the segregated snow to the atmosphere in a single dense stream, and means for effecting discharge of the segregated vapors to the atmosphere as several streams arranged to merge and encircle or surround said snow stream.

17. Fire extinguishing apparatus for discharging liquid carbon dioxide, comprising a chambered body, a tubular stem carried by the body and having an orifice through which liquid carbon dioxide may be released into the interior of the body to form a mixture of snow and vapors therein, means within the body for causing the snow and the vapors of the mixture to become segregated while flowing therethrough, means operatively associated with the segregating means to effect separation of the segregated snow and vapors, and means for effecting discharge of the separated snow and vapors to the atmosphere.

18. Fire extinguishing apparatus for discharging liquid carbon dioxide, comprising a chambered body, a tubular stem carried by the body and having an orifice through which liquid carbon dioxide may be released into the interior of the body to form a mixture of snow and vapors therein, means within the body for causing the mixture to travel a substantially curvilinear path of sufficient length to cause the difference in density of the snow and the vapors to effect a substantial segregation of these components, means operatively associated with the segregating means to effect separation of the segregated snow and vapors, and means for effecting discharge of the separated snow and vapors to the atmosphere.

19. Fire extinguishing apparatus for discharging liquid carbon dioxide, comprising a chambered body, a tubular stem carried by the body and having an orifice through which liquid carbon dioxide may be released into the interior of the body to form a mixture of snow and vapors therein, means within the body for causing the snow and vapor mixture to be deflected radially out-

wardly in all directions, means within the body for causing the outwardly deflected snow and vapors to change their direction of travel to substantially that of a curvilinear path arranged to direct the said snow and vapors radially inwardly toward the axis of the body, said curvilinear path being of sufficient length to cause the difference in density of the snow and the vapors to effect a substantial segregation of these components, and means for effecting discharge of the segregated snow and vapors to the atmosphere.

20. Fire extinguishing apparatus for discharging liquid carbon dioxide, comprising a hollow body through which a mixture of carbon dioxide snow and vapors passes, and means within the body for separating snow and vapors from each other while passing therethrough and for discharging the same to the atmosphere with the vapors shielding the snow from the atmosphere.

21. A method of discharging liquid carbon dioxide for fire extinguishing purposes, comprising effecting sudden release of the liquid to lower its pressure sufficiently to form a mixture of snow and vapors, effecting separation of snow and vapors from each other and forming the separated snow and vapors into a discharge stream with the vapors shielding the snow from the atmosphere.

22. Fire extinguishing apparatus for discharging liquid carbon dioxide, comprising a chambered body, means for effecting sudden release of liquid carbon dioxide into the interior of the body to form a mixture of snow and vapors therein, means within the body for causing the mixture to travel a substantially curvilinear path of sufficient length to cause the difference in density of the snow and the vapors to effect a substantial segregation of these components, and means for effecting discharge of the segregated snow and vapors to the atmosphere.

23. Fire extinguishing apparatus for discharging liquid carbon dioxide, comprising a chambered body, means for effecting sudden release of liquid carbon dioxide into the interior of the body to form a mixture of snow and vapors therein, means within the body for causing the snow and vapors of the mixture to become segregated while flowing therethrough, and means for effecting discharge of the segregated snow and vapors to the atmosphere in a composite stream with the snow forming the core thereof.

24. Fire extinguishing apparatus for discharging liquid carbon dioxide, comprising a chambered body, means for effecting sudden release of liquid carbon dioxide into the interior of the body to form a mixture of snow and vapors therein, means within the body for causing the mixture to travel a substantially curvilinear path of sufficient length to cause the difference in density of the snow and the vapors to effect a substantial segregation of these components, means for effecting discharge of the segregated snow to the atmosphere in a single dense stream, and means for effecting discharge of the segregated vapors to the atmosphere as several streams arranged to merge and encircle or surround said snow stream.

25. Fire extinguishing apparatus for discharging liquid carbon dioxide, comprising a chambered body, means for effecting sudden release of liquid carbon dioxide into the interior of the body to form a mixture of snow and vapors therein, means within the body for causing the snow and the vapors of the mixture to become

segregated while flowing therethrough, means operatively associated with the segregating means to effect separation of the segregated snow and vapors, and means for effecting discharge of the segregated snow and vapors to the atmosphere.

26. Fire extinguishing apparatus for discharging liquid carbon dioxide, comprising a chambered body, means for effecting sudden release of liquid carbon dioxide into the interior of the body to form a mixture of snow and vapors therein, means within the body for causing the mixture to travel a substantially curvilinear path of sufficient length to cause the difference in density of the snow and the vapors to effect a substantial segregation of these components, means operatively associated with the segregating means to effect separation of the segregated snow and vapors, and means for effecting discharge of the segregated snow and vapors to the atmosphere.

27. Fire extinguishing apparatus for discharging liquid carbon dioxide, comprising a chambered body open at its front, means for effecting sudden release of liquid carbon dioxide into the chamber of said body to form a mixture of snow and vapors, a plurality of flow controlling and directing means arranged in the chamber of said body to receive the mixture of snow and vapors, each of said last mentioned means being constructed to cause the portion of the mixture it receives to travel a curvilinear path of sufficient length to effect segregation of the snow and vapors, and means for effecting discharge of the thus segregated snow and vapors through the open front of the body.

28. Fire extinguishing apparatus for discharging liquid carbon dioxide, comprising a chambered body open at its front, means for effecting sudden release of liquid carbon dioxide into the chamber of said body to form a mixture of snow and vapors, a plurality of flow controlling and directing means arranged in the chamber of said body to receive the mixture of snow and vapors, each of said last mentioned means being constructed to cause the portion of the mixture it receives to travel a curvilinear path of sufficient length to effect segregation of the snow and vapors and to separately release the snow and the vapors into the chamber of said body, and means for effecting discharge of the several segregations of snow and vapors through the open front of the body to form a composite stream.

29. Fire extinguishing apparatus for discharging liquid carbon dioxide, comprising a chambered body open at its front, means for effecting sudden release of liquid carbon dioxide into the chamber of said body to form a mixture of snow and vapors, a plurality of flow controlling and directing means arranged in the chamber of said body to receive the mixture of snow and vapors, each of said last mentioned means being constructed to cause the portion of the mixture it receives to travel a curvilinear path of sufficient length to effect segregation of the snow and vapors and to separately release the snow and the vapors into the chamber of said body, means for collecting the several segregations of snow and discharging them through the open front of the body as a single dense stream, and means for effecting discharge of the vapor segregations through the open front of the body in such a manner as to cause them to merge and encircle or surround the snow stream.

30. Fire extinguishing apparatus for discharging liquid carbon dioxide, comprising a chambered body open at its front, means for effecting

sudden release of liquid carbon dioxide into the chamber of said body to form a mixture of snow and vapors traveling radially outwardly thereof in all directions, flow controlling and directing means arranged in the chamber of said body to receive the radially outwardly traveling mixture of snow and vapors and cause it to travel curvilinearly a sufficient distance to effect segregation of the snow and vapors, means for collecting the segregated snow at the end of its travel and discharging it through the open front of the body as a single dense stream, and means for separating the segregated vapors from the snow and effecting discharge of the vapors through the open front of the body in such a manner as to cause the snow stream to be encircled or surrounded thereby.

31. Fire extinguishing apparatus for discharging liquid carbon dioxide, comprising a chambered body open at its front, means for effecting sudden release of liquid carbon dioxide into the chamber of said body to form a mixture of snow and vapors traveling radially outwardly thereof in all directions, a circular series of radially extending flow controlling and directing means arranged in the chamber of said body to receive separate portions of the radially outwardly traveling mixture of snow and vapors and cause said portions to travel curvilinear paths of sufficient length to effect segregation of the snow and vapors, means for collecting the several segregations of snow from the series of flow controlling and directing means and discharging them through the open front of the body as a single dense stream, and means for effecting discharge of the vapor segregations through the open front of the body in such a manner as to cause them to merge and encircle or surround the snow stream.

32. Fire extinguishing apparatus for discharging liquid carbon dioxide, comprising a chambered body open at its front, means for effecting sudden release of liquid carbon dioxide into the chamber of said body to form a mixture of snow and vapors traveling radially outwardly thereof in all directions, a circular series of radially extending flow controlling and directing means arranged in the chamber of said body to receive separate portions of the radially outwardly traveling mixture of snow and vapors and cause said portions to travel curvilinear paths of sufficient length to effect segregation of the snow and vapors, means for collecting the several segregations of snow from the series of flow controlling and directing means and discharging them through the open front of the body as a single dense stream, and means for releasing the segregated vapors from the series of flow controlling and directing means into the chamber of the body radially outwardly of the region in which the snow segregations are collected so that the vapors can be discharged through the open front of the body in such a manner as to cause the snow stream to be encircled or surrounded thereby.

33. Fire extinguishing apparatus for discharging liquid carbon dioxide, comprising a chambered body open at its front, means for effecting sudden release of liquid carbon dioxide into the chamber of said body to form a mixture of snow and vapors traveling radially outwardly thereof in all directions, a circular series of radially extending flow controlling and directing means arranged in the chamber of said body to receive separate portions of the radially outwardly traveling mixture of snow and vapors and cause said portions to travel curvilinear paths of sufficient

length to effect segregation of the snow and vapors, means for collecting the several segregations of snow from the series of flow controlling and directing means and discharging them through the open front of the body as a single dense stream, and openings formed in the sides of the flow controlling and directing means for releasing the segregated vapors into the cham-

ber of the body radially outwardly of the region in which the snow segregations are collected so that the vapors can be discharged through the open front of the body in such a manner as to cause the snow stream to be encircled or surrounded thereby.

HILDING V. WILLIAMSON.
